UNITED STATES PATENT OFFICE.

MINOTT W. SEWALL, OF ROSELLE, NEW JERSEY, ASSIGNOR TO THE BABCOCK & WILCOX COMPANY, OF BAYONNE, NEW JERSEY, A CORPORATION OF NEW JERSEY.

FURNACE.

941,657.

Specification of Letters Patent. Patented Nov. 30, 1909.

Application filed June 1, 1908. Serial No. 436,080.

To all whom it may concern:

Be it known that I, MINOTT W. SEWALL, a citizen of the United States, residing at Roselle, in the county of Union and State of New Jersey, have invented certain new and useful Improvements in Furnaces, of which the following is a specification.

This invention relates to a furnace for the combustion of fuel and particularly to that 10 class of furnaces provided with mechanical stokers of the chain-grate type.

The object of the invention is to cause a complete combustion of the fuel and the utilization of all of the heat incident thereto, 15 and to provide means for preventing the formation of clinkers. I attain the former by forming a secondary combustion chamber at or near the inner end of the grate and below the same, and the latter by providing 20 means for causing an even and uniform supply of air to pass through the entire fuel bed. With the present methods large quantities of carbon are often found in the refuse and frequently an excess of air is introduced 25 into the furnace to the detriment of economy in operation. The causes of the introduction of an excess of air in the furnace are numerous. One is the coking of the coal and then the cracking open of the crust of 30 coke and the admission of air through the cracks while none passes through the body of the crusted surface. The fire thus soon becomes ragged and lumpy, parts become thoroughly burned out and in other parts 35 the coal is unconsumed and good coke passes on which is discharged with the ash and wasted.

Figure 1 of the accompanying drawing is a longitudinal section of a furnace provided 40 with an ordinary mechanical stoker of the chain-grate type having my improvements applied thereto. Fig. 2 is a transverse section on the plane of the line 2—2 of Fig. 1.

The furnace to which my invention is applied may be of any usual or preferred construction in its general features of construction. That shown in the drawings is represented as provided with a mechanical stoker, A, of the chain grate type. The 45 grate is mounted upon and supported by sprocket wheels a', one of which may be driven by any suitable mechanism. The fuel is introduced into the furnace at the front through a hopper, and is delivered

onto the grate, by which it is carried across 55 the combustion chamber and toward the rear.

E indicates a pit or chamber into which the ash and unburned, or but partly consumed fuel is discharged from the grate. It 60 is situated below the rear end of the latter, and constitutes a secondary combustion chamber in which the remaining combustible constituents of the fuel in what is delivered by the grate may be consumed and 65 the products of combustion therefrom utilized. A transverse bridge wall or partition D separates this chamber E from the main combustion chamber of the furnace. This wall is extended downward at the rear to 70 form the rear curtain wall, b', of the coke and ash pit, behind which is a flue F' leading to the combustion chamber of the furnace. A doorway or a series of doorways or 75 passages, F, are formed in the wall b', and constitute the communications between the pit or chamber and the flue F'. These openings F are at or near the bottom of the pit and are of such size, in vertical dimensions, that they become closed as soon as a small 80 amount of material has been discharged by the grate. The chamber E has communication at the front with the air supply, the air passing through the hot grate bars, as indicated by the arrows at M, and at the rear 85 communicates with the air-inducing means, as the stack, through the flue F', so that air is caused to pass downwardly through the mass of ash and unconsumed and burning fuel that gradually accumulates 90 therein. The chain grate A provides means for automatically feeding fuel to the main combustion chamber, and for feeding partially burned fuel to the secondary down draft combustion chamber. 95

A damper, G, is located in the flue F', by which the latter is opened or closed as may be desired.

H H indicate dumping doors at the bottom of the chamber E, to permit the removal 100 of the ashes therefrom.

The front wall of the secondary combustion chamber is inclined upward, extending from the dumping doors, H, into close proximity to the lower run of the chain grate, as 105 indicated at L. This wall directs into the secondary combustion chamber any pieces of unconsumed fuel that may fall through the

rear parts of the grate. The hot gases incident to the combustion taking place within the chamber E pass into the main combustion chamber of the furnace and there mingle with the hot products of combustion from the main fuel bed, and are conducted away for utilization. Thus I not only consume the unburned parts of the fuel carried over the end of the grate but I utilize immediately the heat incident to that combustion.

In order to prevent the formation of cracks or openings at the rear end of the grate, where the grate bars turn and the ash and unburned fuel are discharged, and thereby provide free passages for the air, which naturally seeks such free openings, rather than to pass through the bed of fuel on the grate and to control the feed of fuel to the secondary down draft furnace. I arrange a dam or retarding device near the rear end of the grate and a little above the upper plane thereof. Against this retarding device, which is arranged transversely across the furnace, the upper layers of the fuel are fed by the onward moving grate and caused to bank, thus effectually closing the fire chamber at the rear, and tending to maintain a uniform depth of fuel throughout all portions of the furnace. I prefer that this retarding device or dam should be in the form of a water box B. This water box is mounted between the front or forward end of the wall D and the upper surface of the grate. By arranging the box at this point the formation of clinkers at the rear of the grate is largely prevented.

N indicates side wall water boxes arranged longitudinally of the furnace and having inlet and outlet pipes n and n' respectively. I have shown these water boxes as bearing directly against the grate. It is obvious, however, that a plate or a course of fire brick may intervene between the boxes and the grate. By this construction the air supplied to the grate is prevented from escaping at the sides thereof. The object of the water boxes is to prevent the formation of clinkers on the furnace walls and the destruction thereof caused by the removal of such formation.

It is well known that the formation of clinkers on the side walls causes a disturbance of the fuel bed, with the result that air holes or cracks are formed therein. This causes the escape of air to the combustion chamber which is detrimental to the economical operation of the furnace and also causes the fuel to burn out in some parts, while leaving other parts unconsumed as already described.

It will be seen that in a furnace, such as I have described no clinkers can form on the side and end walls; also that the fuel bed is being continually packed at the rear end, with the result that there is a uniform sup-

ply of air to all parts of the fire; and that therefore better conditions of combustion are obtained.

The extension of the chain grate into the secondary down draft furnace causes all air passing through the rear of the grate to pass either through the fuel on the grate or that in the secondary down draft furnace and thence to the main combustion chamber, thus providing means for a draft of air through the fuel in the secondary chamber and at the same time preventing any passage of excess air into the main combustion chamber through an effort to consume the fuel in the secondary chamber.

What I claim is:—

1. A furnace comprising a main combustion chamber, a secondary combustion chamber arranged to receive the unconsumed fuel from the former, the furnace being provided with an independent flue for the gases from the secondary combustion chamber.

2. A furnace comprising a main combustion chamber, a secondary combustion chamber arranged to receive the unconsumed fuel from the former, and a wall separating the two chambers and spaced from the furnace wall, to form an independent flue for the gases from the secondary combustion chamber.

3. A furnace comprising a main combustion chamber, a secondary combustion chamber arranged to receive the unconsumed fuel from the former, a wall separating the two chambers and spaced from the furnace wall to form an independent flue for the gases from the secondary combustion chamber, and a damper in said flue.

4. A furnace comprising a main combustion chamber, a secondary combustion chamber arranged below and receiving the unconsumed fuel from the main chamber, a wall separating the two chambers and spaced from the furnace wall to form an independent flue for the gases from the secondary combustion chamber whereby a down-draft of air from the main supply is provided for said secondary chamber.

5. A furnace comprising a main combustion chamber; a secondary combustion chamber, a chain grate for feeding fuel through the former and discharging it into the latter chamber, a bottom wall for said secondary chamber extended upward and forward into close proximity to the lower roof of the chain grate, and a wall separating the two chambers and spaced from the furnace wall to form an independent flue for the gases from the secondary combustion chamber.

6. A furnace comprising a main combustion chamber, a chain grate therefor, a secondary combustion chamber below the main chamber into which said grate is extended, and a wall separating the two chambers and

spaced from the furnace wall to form an independent flue for the gases from the secondary chamber and to cause a down-draft of air from the main supply through the 5 secondary chamber.

7. A furnace comprising a main combustion chamber, a chain grate therefor, a secondary combustion chamber into which said grate extends, a water box dam at the rear 10 of the grate to control the feed of fuel thereto from the secondary combustion chamber, and a bridge wall having a downward extension separating the two chambers, said extension being spaced from the furnace 15 wall to form an independent flue for the gases from the secondary combustion chamber whereby a down-draft of air from the

main supply is provided for the secondary combustion chamber.

8. A furnace comprising a main combustion chamber, a secondary combustion chamber arranged to receive the unconsumed fuel from the former, a water box dam to control the feed of fuel to said secondary chamber, water boxes at the sides of the grate for the purpose described, and a wall separating the two chambers and spaced from the furnace wall to form an independent flue for the gases from the secondary combustion chamber. 20 25
